UNITED STATES PATENT OFFICE.

MENOTTI NANNI, OF CHICAGO, ILLINOIS.

SAFE.

1,283,866.

Specification of Letters Patent.

Patented Nov. 5, 1918.

Application filed July 31, 1916. Serial No. 112,448.

To all whom it may concern:

Be it known that I, MENOTTI NANNI, a subject of the King of Italy, residing at Chicago, in the county of Cook and State 5 of Illinois, have invented a certain new and useful Improvement in Safes, of which the following is a specification.

This invention relates to improvements in safes and has for its object to provide a new 10 and improved safe particularly adapted to be used on vessels and to automatically disengage itself from the vessel in case the vessel is sunk, and float upon the water so as to preserve whatever articles may be placed 15 therein.

The invention is illustrated in the accompanying drawings, wherein—

Figure 1 is a cross sectional view of a vessel showing one form of the safe in position;

Fig. 2 is an enlarged sectional view with parts omitted showing the outer casings and inner buoyant sections;

Fig. 3 is an enlarged longitudinal sectional view through one of the buoyant sections;

Fig. 4 is an enlarged sectional view taken on line 4—4 of Fig. 3;

Fig. 5 is an enlarged sectional view taken 30 on line 5—5 of Fig. 2;

Fig. 6 is a sectional view through the cover;

Fig. 7 is a view on line 7—7 of Fig. 6;

Fig. 8 is an end view of one of the drawers 35 or receptacles of the buoyant section;

Fig. 9 is an enlarged view showing one of the keys therefor.

Like numerals refer to like parts throughout the several figures.

Referring now to Fig. 1, I have shown a vessel 1, with my safe in position. In this construction the safe is made up of an outer inclosing and protecting part which is preferably fastened to the vessel, and an inner 40 floating section into which the articles are received, located within the outer part and adapted to automatically disconnect itself from the vessel when the vessel is sunk. In the construction shown I provide an outer 45 casing 2 of strong resisting material. This outer casing may be made of any strength desired. Within this outer casing is an inner casing 3, and within the inner casing are one or more floating or buoyant sections 4. 50 Some means is provided for permitting the water to get into the inner section 3 in case

the vessel is sunk, so that the buoyancy of the floating sections will be brought into action to cause them to be discharged from the inner casing and rise to the surface of the water. Any desired construction may be used for this purpose. As herein shown, I provide at the top of the casings 2 and 3 a suitable cover 5, which covers the entire open ends of the two casings. This cover is provided with a safety valve 5^a. The inner casing 3 is provided with suitable openings or perforations 6. The cover 5 is arranged so that it will float in the water, and when the vessel sinks this cover rises in the water 70 and opens the ends of the casings. The water then passes down between the casings 2 and 3 and enters the casing 3, thus causing the buoyancy of the floating sections 4 to act to cause them to rise and be discharged from the inner casing. In the construction shown, I have illustrated an inner section 4 arranged at the various decks so that each deck can have its own safe, thereby making it unnecessary for the passengers on one deck, such for example, as the steerage passengers, to go to the upper deck to place 80 their valuables in the safe or get them out of the safe. The casings 2 and 3 opposite each safe are provided with suitable doors 7 and 8 so that by opening the doors access can be had to the floating section 4 on each deck. At each deck I have shown the casings 2 and 3 as connected by the perforated pieces 2^a. One of the buoyant sections is 90 preferably arranged to contain the important mail on the boat, such for example, as the section 4^a. I prefer to form the lower section 9 simply as a float, the float preferably being sealed so that its buoyancy cannot be reduced. This float 9 is connected with a cable 10, which is wound on a reel 11. When the ship is sunk, the buoyancy of this float causes it to unwind the cable on the reel and rise to the surface, thus designating the place where the ship is sunk. This float is provided with the name of the vessel, and there is associated with it any other information desired about the vessel or its cargo, passengers, crew, destination 105 and the like. The cable 10 is of sufficient length to permit the float to rise to the surface, this length depending upon the depth of the water on which the vessel is used.

Referring now to the construction of the 110 buoyant sections 4, such sections have an outer part or shell 12, which is preferably

stationary when the safe is in position and which contains suitable buoyant material 13, which is preferably located at both ends and between the walls of the section, the sections 5 being provided with double walls as indicated. Within the outer part or shell are one or more movable or revolving sections 14, 14^a, 14^b. In Fig. 3 I have shown three such sections. The revolving sections may 10 be mounted in any desired manner, and as herein shown, may rotate about a central part or axis 15. These sections may be provided with ball-bearings 16 so that they may be easily rotated. In the drawing the central part 15 is shown as consisting of a tube through which passes a rod 15^a, this rod having an enlarged end 15^b which engages the lower end of the tube and the wall 15^c. The upper end of this rod is provided with a 15 ring 15^d, the whole being arranged so that by attaching a lifting device to the ring 15^d the section will be lifted, as for example, to lift it out of the water or when placing it in position or for any other purpose. In order 20 to secure the buoyant effect of the water it is necessary that the water shall enter the casings 2 and 3. It is therefore desirable to provide some safety device so that the water will enter these casings even if for any reason 25 the cover 5 is not removed. In order to secure this result I provide the cover with a suitable safety valve for this purpose. The safety valve 5^a of the cover 5 may be arranged in any desired manner. As shown in 30 Fig. 6 this safety valve consists of a tube 5^b. This safety valve is arranged so that if when the ship sinks some heavy body should fall on the cover 5 and hold it against removal or if it should be held in place for any other 35 reason the safety valve would be operated to permit water to enter the casings surrounding the floating sections. The water will enter through the openings 5^b. The revolving sections are provided with a series of 40 drawers or receptacles extending around their periphery and into which the valuables of the passengers and any other articles may be placed. These drawers or receptacles may be made in any desired manner. As 45 herein shown, each of these drawers or receptacles is located within a casing 17 closed at one end and open at the other end, said casing being fastened at one end to the inner wall 18 and at the other end to the outer wall 50 19. In the drawing I have shown the casing as fastened by rivets. The drawer or receptacle is shown as consisting of two telescoping parts 20 and 21. The part 21 55 encloses the part 20, said parts being open at opposite ends as shown. The part 20 is provided with the overlapping end piece 22, which overlaps the joint between the two parts of the receptacle and between the receptacle and the casing 17, so as to form a 60 water-tight joint. These several receptacles

or drawers are numbered as shown in Fig. 8 or otherwise designated and each receptacle is provided with a lock and key 23 for the passenger. (See Fig. 9.) This key is preferably provided with a means, such as a strap 24, for fastening it to the passenger's wrist so that in the event the passenger is drowned, his valuables and the data, such as his name, address, etc., can be ascertained by opening the receptacle marked with the corresponding number. These receptacles, in addition to having the valuables of the passengers, will also have their names and addresses, the names and addresses of their friends, and any other data that may be 75 valuable in the case of death of the passengers. The lock 25 herein shown, is provided with a bolt 26, which when the lock is locked, passes through the three parts 20, 21 and 17, so as to lock the drawer in the 80 casing. The attendant on the boat will also have a key, which will simply move the bolt sufficient to disconnect it from the casing 17 but not to unlock the two parts 20 and 21. The passenger's key will then move the bolt 90 to unlock these two parts. The drawer can then be opened without disturbing any of the articles therein, by simply placing it on a support with the lock side down, and then lifting or removing the part 21. The sections 4 are provided with doors 27, one for each revolving section. These doors are preferably arranged to be water-tight, as illustrated in Fig. 4. In this construction each door 27 is provided with a bar 28 100 through which passes a screw-threaded rod 29 having an end 30 to receive a wrench or handle, there being a spring 31 on the rod 29. When the door is placed in position, the bar 28 is moved so as to engage the section at the sides of the door as illustrated in Fig. 4, there being a stop 32 which limits its rotation and holds it in its position while the rod is being rotated to draw the door tightly in position. The revolving sections 110 are arranged so that they can be rotated to successively bring the different drawers in front of the door. Any suitable means for this purpose may be used. As herein shown, each section is provided with a rack 33 (see 115 Figs. 2, 3 and 4), which is engaged by a pinion 34 on a shaft which projects through the section and is provided with an end 36 adapted to receive a handle 37. It will be seen that by rotating the handle 37 the revolving section may be rotated so as to bring any one of the drawers or receptacles opposite the door. The revolving sections are also provided with buoyant material 38 and the arrangement is such that even if all portions of the section which will contain water, should be filled with water, the section would still float. One or more of the sections, as for example, the section 4^a, may be arranged to hold valuable mail so that this 120 125 130

mail would be saved if the boat sank. It is of course evident that the safe may be used to hold anything desired, and that such safes will be burglar-proof and fire-proof, it being possible to make the safe just as strong as desired.

If, now, the ship should sink, the cover 5 comes off and the water enters the casings 2 and 3, there being means provided for it 10 to quickly and easily pass from casing 2 into casing 3, as for example, the perforations in casing 3. The buoyant sections then become immersed in the water and their buoyancy causes them to be ejected 15 from the casings and float to the top. It will thus be seen that the portions of the safe containing the valuables are automatically removed from the vessel when the vessel sinks. These sections then float upon the 20 water and can be recovered and the articles therein removed. The heavy outer protecting parts are left on the ship. The section 9 also floats to the top, and since it is connected with the vessel by the cable 10, it indicates the location of the sunken vessel. If something should fall upon the cover 5 so as to prevent its easy removal, then the safety valve will permit the water to enter the casings and cause the buoyant sections 30 to be ejected.

This construction can be installed in either old or new vessels without taking the vessel to the drydock. The sections of the safe are held in position so that they will 35 not be moved by the movements of the vessel. I may also provide the spaces between the casings 17 with the buoyant material. When a buoyant section is used for mail, for example, the revolving sections will be 40 omitted so as to give more space.

I have described in detail a particular construction embodying my invention, but it is of course evident that the parts may be varied in many particulars without departing 45 from the spirit of the invention, and I therefore do not limit myself to the particular construction shown.

The buoyant material used may be of any desired form but is preferably of solid material such as cork and cement or glue.

I claim:

1. The combination with a vessel, of an outer casing extending through a portion of the vessel, an inner casing located within the 55 outer casing and separated therefrom by a space, a buoyant section located within the inner casing, doors in said casing and said buoyant section, arranged to register, a revolving section contained within the buoyant section, said revolving section provided with a series of receptacles, and mechanism for revolving said revolving section to bring any of said receptacles opposite said doors, and means for admitting water into 60 both of said casings in the event the vessel

is sunk so as to cause the buoyancy of said buoyant section to automatically discharge it from the inner casing.

2. The combination with a vessel, of an outer casing extending through a portion of the vessel, an inner casing located within the outer casing and separated therefrom by a space, a buoyant section located within the inner casing, doors in said casing and said buoyant section, arranged to register, a revolving section contained within the buoyant section, said revolving section provided with a series of receptacles, buoyant material contained within said buoyant section and within said revolving section, and mechanism for revolving said revolving section to bring any of said receptacles opposite said doors, and means for admitting water into both of said casings in the event the vessel is sunk so as to cause the buoyancy of said buoyant section to automatically discharge it from the inner casing.

3. The combination with a vessel, of an outer casing extending through a plurality of the decks of the vessel, an inner casing smaller in diameter than the outer casing and also extending through a plurality of the decks of the vessel, the inner casing and outer casing separated by a space, a buoyant section in the inner casing adapted to contain articles, water connections leading from the space between the two casings into the inner casing, a buoyant removable cover at the upper end of said casings for covering both of said casings and adapted to be automatically removed when the vessel sinks so as to permit water to enter said casings and discharge the buoyant section therefrom.

4. The combination with a vessel of an outer casing extending through a plurality of the decks of said vessel, an inner casing smaller in diameter than the outer casing and also extending through a plurality of the decks of said vessel, a buoyant section located within the inner casing, a revolving section within the buoyant section, said revolving section consisting of an inner wall and an outer wall, a series of casings closed at one end and extending between the two walls and fastened to said walls, and a receptacle in each of said casings, a door in said buoyant section, and means for revolving the revolving section so as to bring any of said receptacles opposite said door.

5. The combination with a vessel, of a safe comprising an outer casing extending through the deck and open at its upper end, an inner casing smaller in diameter than the outer casing, also open at its upper end, a buoyant section located within the inner casing and adapted to receive articles, the buoyant section being automatically discharged from said casing when the casings are filled with water.

6. A safe comprising a section having an

outer casing, an inner revolving section within said casing, a series of casings connected with said revolving section, closed at their inner ends and open at their outer ends,
5 a receptacle in each of said casings comprising two telescoping parts open at opposite ends.

7. A safe comprising a section having an outer casing, an inner revolving section
10 within said casing, a series of casings connected with said revolving section, closed at their inner ends and open at their outer ends, a receptacle in each of said casings comprising two telescoping parts open at opposite ends.

site ends, a lock having a bolt which extends 15 through the casing and the two telescoping parts, said bolt adapted to be moved by one key to disconnect it from the casing and by another key to disconnect it from one of the telescoping parts.
20

In testimony whereof, I affix my signature in the presence of two witnesses this 24th day of July 1916.

MENOTTI NANNI.
